UNITED STATES PATENT OFFICE.

ERNEST GILLERT, OF ST. LOUIS, MISSOURI.

IMPROVEMENT IN VAPOR-BURNERS.

Specification forming part of Letters Patent No. **106,574**, dated August 23, 1870.

To all whom it may concern:

Be it known that I, ERNEST GILLERT, of the city and county of St. Louis, State of Missouri, have invented a new and useful Improvement in Vapor-Burners; and I declare the following to be a full, clear, and exact description of the same, reference being had to the annexed drawings, which are made a part of these specifications.

The object of this improvement is the combination, with a vapor-burner, of a heating apparatus for generating the vapor, which will make a steady, regular heat, perfectly protected from effects of air-currents, thereby insuring perfect combustion.

That others may be enabled to understand the nature of my invention, I will proceed to describe it with reference to the annexed drawings.

Figure 1 is an outside view of the burner complete. Fig. 2 is a sectional view of burner. Fig. 3 is a sectional view of burner.

Similar letters of reference indicate corresponding parts in all the figures.

Letter A, Figs. 1, 2, 3, is the burner. Letter B, Figs. 1, 2, 3, is a heating-cylinder, closed at top and open at bottom. Letter C, Figs. 2 and 3, are two flanges putting out from the burner A at an angle of about thirty-five degrees, converging at the top, and dividing the space between the burner A and the cylinder B; letter D, a small chamber, and letter E a large chamber. Letter G, Figs. 2 and 3, is an arm putting out from burner A to steady cylinder B in its place. Letter H is a packing, of wick

or its equivalent, to regulate the flow of fluid. Letter I is a governor to regulate the size; letter J, the illuminating-flame. Letter K, Figs. 1 and 2, is an inverted flange covering an aperture for the admission of air for mixture with the vapor as it passes; letter L, the gas-chamber. Letter M, Figs. 2 and 3, is a small perforation in the burner A, for the escape of gas from gas-chamber L into the small chamber D, for the supply of a small blue heating-flame, which passes downward in chamber D, around the lower extremity of the two flanges C, and upward in large chamber E, a draft being formed through N, Figs. 1 and 2, the draft-hole.

By this means the heating-flame is protected from the wind, the burner is entirely encircled by the heating-flame, and, having the further protection of the cylinder B, is not liable to become chilled, and the vapor condensed by cold drafts of air.

What I claim as my invention, and for which I desire to obtain Letters Patent, is—

1. The combination, with the burner A, of flanges C C.
2. The division of the cylinder B into chambers or flues D and E, for the purpose of forming a draft to the heating-flame, which is supplied with gas or vapor from the perforation M, substantially as set forth in drawings and specifications.

ERNEST GILLERT.
